UNITED STATES PATENT OFFICE.

SAMUEL POLLOCK, JR., OF MOUNT AUBURN, IOWA.

POST OR STAKE PULLER.

Application filed November 3, 1927. Serial No. 230,788.

This invention relates to certain new and useful improvements in post or stake pullers, and it has for its object, among others, to provide a simple, efficient, strong and durable device for quickly and easily extracting a post, stake, pipe, or any other device from the ground or other place where it may be located. It will be found useful in lifting a pipe from an oil well or lifting or raising any element by which it may be caused to grasp.

The invention has for an object, among others, to provide a post or stake puller, of a portable nature, capable of being set up in the desired position and readily applied to the post or rod, the latter being readily lifted and a new grip automatically obtained thereupon after each raising of the post or rod.

It has for a further object to provide a device of this character, quickly adjustable for use upon posts, rods or the like of different diameter and of any cross section.

The device embodies two parts, both capable of being manufactured at small cost, possessing great strength, and not requiring skilled labor to apply or manipulate the same.

Other objects and advantages of the invention will hereinafter appear and the novel features thereof will be particularly pointed out in the appended claims.

The invention, in its preferred form, is clearly illustrated in the accompanying drawing, which with the numerals of reference marked thereon, form a part of this specification, and in which,

Fig. 1 is a front view showing the device applied to a rod.

Fig. 2 is a side elevation of the same, showing the operating lever and the gripping means in full and dotted line positions.

Fig. 3 is a top plan view of Fig. 2.

Fig. 4 is an enlarged top plan view with the operating handle broken off showing the chain-holding member, which latter serves a further function, soon to be described.

Fig. 5 is a side elevation of the chain-holding member, the operating handle being broken away.

Fig. 6 is a face view of the chain-holding member, and

Fig. 7 is a side elevation with a portion in broken lines, showing a modified construction.

Like numerals pertain to like parts throughout the general views.

Referring to the drawings, 1 designates the upright or supporting member which may vary in the form and construction, but in the present invention shown as being of substantial form, the base 2 of which is designed to rest upon the ground or other support, the side members at their upper end being drawn parallel to each other and extended slightly above their bend to form the flanges 3 between which is mounted upon a suitable pivot 4, an operating handle 5.

As seen in Figs. 2 and 5, the operating lever 5 is extended beyond its pivot to form a short arm 6 to the free end of which is pivotally mounted the member 7. The construction and character of this member 7 will be best understood by reference to Figs. 4, 5 and 6, in which it is shown as a combined dog and chain-receiving member, the same having the spaced-apart jaws or the like 8 (see Fig. 4), between which is pivoted upon the pivot pin 9 the end of the short arm 6 of the operating lever 5.

The member 7 is formed upon opposite sides of the portion 8 with lugs or ribs 10 (see Figs. 4, 5 and 7) to add strength to the same, and what may be termed the forward end of this member, is provided with the substantially V-shaped notch 11 and intermediate said notch and the rear end of such member, are openings 12 all of which will be clearly seen from reference to Fig. 4.

The member 7 is provided with the upwardly extending portions 13, having openings 14 extending transversely and which serve for the reception of a cotter pin 15, as indicated by dotted lines in Fig. 4 and full lines in Fig. 3. In one form of the invention, soon to be described, the cotter pin forms a double function. In the form shown in Figs. 2, 4, 5 and 6, it serves to prevent displacement of the chain, while in the form shown in Fig. 7, it serves not only this last mentioned function, but also serves as the means of pivotal connection between the ends of the short member 6 of the lever and the member 7. It is to be understood that in this last connection or arrangement, that is, where the cotter pin serves the double purpose above mentioned, the pivot 9 heretofore described as being that upon which the operating lever had pivotal connection with the member 7, is omitted.

16 is a piece of chain or the like, the ends of which are passed upwardly through the openings 12 of the member 7, leaving the bight of the chain depending, and the ends 5 of the chain are then passed through the opening 17 in the jaws of the member 7, resting upon the walls 18 thereof, and the cotter pin 15 is disposed above the chain in said openings, the chain being first passed around the 10 post or other object 19 to be lifted.

The full line position of the lever or operating member 5, the member 7 and the chain 16, is that of the parts prior to manipulation of the member 5. With the parts in 15 this position the post or rod 19 is loosely received within the bight of the chain. As the lever is moved from the full line position to that shown in dotted lines in Fig. 2, the post or rod is held in a tight grip between the 20 bight of the chain and the angular walls of the notch 11, and the post or rod is lifted. The arm 5 then being again raised from the dotted to full line position, the chain is automatically released from its hold on the member 25 19 and falls to the full line position, when repetition of these movements alternately grips and releases the member 19 until it is eventually pulled from the ground.

When the cotter pin 15 is in position over 30 the chain, the latter is held fixedly in adjusted position. If it is desired to grasp a larger or smaller post 19 the pin is moved in its bearings until one end of the chain is disengaged when the same may be moved through 35 its opening in one direction or the other to increase or decrease the bight of the chain.

In the construction shown in Fig. 7, the operation of the parts is substantially the same as in the other form but the pin 15^a serves 40 both as the pivotal connection between the free end of the short arm 6 of the operating member 5, and the portion 13 of the member 7.

It is to be noted that the member 7 is in both instances gravitatingly mounted upon 45 the arm 5, so as to automatically drop into holding position after the lever is moved.

Modification in detail may be resorted to without departing from the spirit of the in-

vention or sacrificing any of its advantages. 50 What I claim is:—

1. In a pulling implement, a member having vertical openings and a rod-engaging notch and jaws with openings for the reception of a rod-engaging element threaded through said openings. 55

2. In a pulling implement, a member having vertical openings and a rod-engaging notch and jaws with openings for the reception of a rod-engaging element threaded through said openings, and strengthening 60 ribs. 65

3. In a pulling implement, a member having vertical openings, a notch at one end interspaced with said openings, and passages on the opposite sides of said openings and strengthening ribs at said passages. 65

4. In a pulling implement, a member having vertical openings, a notch at one end interspaced with said openings, and passages on the opposite sides of said openings and 70 strengthening ribs at said openings, and spaced-apart jaws between said passages. 75

5. A pulling implement comprising a support, an operating lever pivotally mounted thereon, a clutch member pivotally carried 75 by said operating member and having a notched free end to engage the object to be pulled, and a flexible gripping member carried by the clutch member to cooperate with the said notch to form a grip on the said 80 object. 85

6. A pulling implement comprising a support, an operating lever pivotally mounted thereon, a clutch member pivotally carried by said operating lever and having a notched free end to engage the object to be pulled, and a flexible gripping member carried by the clutch member to cooperate with and acting in opposition to said notch to form a grip on the said object. 90

7. A pulling implement in accordance with claim 5 in which the clutch member has openings for the passage of said flexible member.

In testimony whereof I affix my signature.

SAMUEL POLLOCK, JR.
